CARBURETOR

Owen L. Garretson, Detroit, Mich., assignor to
 Phillips Petroleum Company, a corporation of
 Delaware

Application September 22, 1941, Serial No. 411,929

1 Claim. (Cl. 261—69)

This invention relates to carburetors, and more particularly it relates to a carbureting device for use with internal combustion engines wherein volatile liquid fuels of essentially any vapor pressure, ranging from the vapor pressure of present day commercial gasoline to such high vapor pressure fuels as natural gasoline and liquefied petroleum gases, may be used.

An object of this invention is to provide a method and apparatus for carbureting very volatile or high vapor pressure liquid fuels or liquefied petroleum gases for use in internal combustion engines.

Another object of this invention is to provide a carburetor of simple and compact design, with few adjustments for use with high vapor pressure liquid fuels.

Another object of this invention is to provide a carburetor for use with high vapor pressure liquid fuels which will permit the metering of liquid fuel to give an air-fuel ratio essentially in accordance with throttle requirements.

Still another object of this invention is to provide a method and apparatus for carbureting high vapor pressure liquid fuels for use in aircraft engines as well as in automotive engines.

Yet another important object of this invention is to furnish a carburetor for use with high vapor pressure fuels for automotive and aircraft engines which will be sensitive, rapid in response to the throttle and free from premature ebullition or vapor lock.

Still other objects and advantages will be apparent to those skilled in the art from a careful study of the following detailed disclosure.

The figure represents one embodiment of my invention directly applicable for use with internal combustion engines where high vapor pressure hydrocarbons or mixtures thereof are used as fuel.

Referring to the figure, numeral 1 represents the air inlet tube with the air flowing in the direction as indicated by the arrow. The air flows in accordance to intake manifold suction as controlled by the butterfly throttle valve 2. Constriction 3 in the air inlet tube serves as a Venturi tube and is placed in the air inlet line just previous in terms of direction of air flow to the throttle 2. Passing through the thickened Venturi wall is an opening 4 for connecting chamber 5 to the air inlet tube 1. Diaphragm 7 of conventional design separates chamber 6 from said chamber 5. Tube 10 connects chamber 6 with the air inlet 1 for equalization of pressure or more specifically for maintaining the air pressure in

chamber 6 equal to that of the incoming air in the air inlet. To one side of the diaphragm 7 is attached rigidly the push pin 11 which extends from the said diaphragm through chamber 6 and opening 4, across the throat of venturi 3, through fuel tube 12 as shown, through opening 13, valve head 14 and terminates in a rigid connection to diaphragm 15. Tension spring 8 is fastened to diaphragm 7 and the tension of this spring is regulated by the adjusting nut or other conventional adjusting apparatus 9. The tension in said spring is so adjusted that the synthetic rubber face 17 of valve head 14 contacts the valve seat 16 thereby preventing flow of liquid fuel from chamber 18 into the vaporizing portion 19 of the air inlet during periods of inoperation. In some cases spring 18 may be in compression to partially balance liquid pressure on valve 14. The valve is then held closed at rest by liquid pressure. Pipe 20 is the fuel line for the conduction of liquid fuel from the fuel storage tank, not shown, to the carburetor, and terminates in compartment 21 which may be maintained under the same pressure as the said fuel storage tank. However, a pressure slightly above the fuel vapor pressure is ordinarily preferred to prevent vaporization through valve 23 and for this purpose a pump may be employed. Tube 22 connects liquid fuel pressure chamber 21 with liquid fuel feed chamber 18 and has a valve or orifice 23, fuel flow therethrough establishing a pressure differential on diaphragm 15 urging valve 14 closed and balancing the opposing force exerted by diaphragm 7.

Tube 24 connects chamber 6 with the air inlet tube at a point on the downstream side of the throttle valve 2 and serves to increase suction on diaphragm 8, insuring proper flow of fuel to the inlet tube during idling when low pressure exists on the downstream side of the throttle valve. Valve or orifice 25 is inserted in this tube 24 for adjustment of the amount of suction for motor idling.

In the operation according to my invention, air is drawn through the air inlet tube 1 by suction from the intake manifold, not shown, and flows through my carburetor in the directions as shown by the arrow. When the air passes the constriction in the air passage or venturi 3, suction set up by said venturi is communicated through opening 4 in the wall of the venturi into the air chamber 6. By such suction the air pressure in chamber 6 is reduced slightly, for example, from a fraction of 1 to say 20 or 25 inches of water. Chamber 6 is maintained at essentially

atmospheric or nearly atmospheric pressure by the air pressure equalizer tube 10 which connects said chamber 6 with the carburetor air intake 1. In case an air cleaner is used, the pressure in the air intake 1 and chamber 6 will be slightly lower than atmospheric due to resistance to air flow through the cleaner. This slight pressure drop or differential is immaterial in the operation of my invention, the important point being to maintain essentially equal pressures in said chamber 6 and air inlet 1.

The pressure of air in chamber 5 being reduced by the action of the intake air passing through the venturi causes a pressure differential to act on diaphragm 7, causing the latter to move in the direction of the reduced pressure. This slight diaphragm movement is transmitted through the rigid push pin 11 causing valve 16 to open, thereby permitting flow of liquid fuel from liquid fuel feed chamber 18. The liquid fuel on passing through the slight opening of valve 16 experiences a pressure reduction which causes ebullition and vaporization. The liquid and newly formed vapor pass through opening 13 into tube 12 and thence into the air stream in the vaporizing portion 19 of the air inlet tube for vaporization and mixture with the air. The flow of the thus formed combustible fuel mixture into the intake manifold and thence into the cylinders is controlled by the butterfly throttle valve 2 of conventional design.

Line 20 carries liquid fuel from the fuel supply tank, not shown, to my carbureting device. Fuel in this fuel tank may be maintained under atmospheric pressure, its own vapor pressure, or under superatmospheric pressure.

Liquid fuel from the said supply tank enters the carburetor in the liquid fuel pressure chamber 21, and flows then through tube 22 into the liquid fuel feed chamber 18. Valve or orifice 23 in tube 22 restricts or controls the flow of liquid fuel from pressure chamber 21 to feed chamber 18 to maintain a pressure differential between these two fuel chambers when liquid fuel is flowing through valve 16. This pressure differential acts on diaphragm 15 tending to close valve 16 and reduce the flow of liquid fuel. The magnitude of the pressure differential is a function of the rate of fuel flow. However, in actual operation, the above explained air pressure differential acting on diaphragm 7 balances the pressure differential set up on diaphragm 15. The net result of this combined operation is to maintain an equilibrium in which the fuel valve is maintained open to an extent dependent on air velocity through inlet tube 4. The diaphragms are so selected or manufactured that they possess the proper rigidity to permit operation under stress of the relatively low pressure differentials which exist in my carbureting device.

Spring 8 is so adjusted by adjuster 9 which may be of conventional design, that during periods of inoperation the valve 16 is closed, thus permitting no flow or leakage of fuel. The spring must be positive in its action when properly adjusted, and yet not of sufficient strength to interfere with the operation of the diaphragms 7 and 15 and valve 16. The tension or compression adjustment of spring 8 will depend to a great extent on the relative size of valve orifice 16, diaphragms and vapor pressure of the fuel. In some cases the spring may be omitted entirely.

Valve or orifice 23 in tube 22 is so adjusted that there is only a relatively small pressure drop therethrough. This relatively small pressure

drop is necessitated by the fact that only a small pressure drop is available for actuating diaphragm 7, and the diaphragms 7 and 15 are of essentially the same size in the preferred embodiment of my invention. However, it is not necessary that the said diaphragm be the same size, since the air pressure actuated diaphragm 7 may be some larger or even considerably larger in area than the liquid actuated diaphragm 15, or may even be some smaller but preferably not appreciably smaller and yet impart sufficient force to the push pin 11 to operate the fuel metering valve 16.

In starting an engine equipped with my carburetor as herein disclosed, the following steps of operation or actuations will take place. When the motor is turned a partial vacuum is set up within the intake manifold, not shown, and communicated to the air inlet of my carbureting device. The rush of intake air through the venturi 3 sets up a suction through opening 4 which reduces the pressure in chamber 5, thereby causing diaphragm 7 to move in the direction of the lower pressure, thereby opening valve 16. A butterfly choke may be employed between line 10 and the venturi to increase the pressure differential for starting. As long as there is no flow of liquid fuel through valve 16, no pressure differential operates against diaphragm 15, and the air operated diaphragm causes valve 16 to open. Upon opening of this fuel valve liquid passes therethrough and a pressure differential is set up between liquid fuel pressure chamber 21 and liquid fuel feed chamber 18 opposing the force of the air diaphragm. If the motor does not start upon the first turnover, as soon as it comes to rest, no pressure differentials exist and tension spring 8 closes metering valve 16 and fuel ceases to flow. If following the turnover or cranking operations as described, the engine starts, the rush of air through venturi 3 is increased, pressure differential on diaphragm 7 is increased tending to meter a larger volume of liquid fuel through valve 16 and similarly a greater pressure differential then operates against diaphragm 15 tending to oppose further opening of said metering valve 16. As soon as the engine has started, the said pressure differentials reach an equilibrium and the metering valve 16 remains fixed in position allowing a fixed amount of liquid fuel to pass if there is a constant air flow into the engine. These conditions remain constant until the throttle valve 2 is changed by the operator when a new set of equilibrium conditions is reached in accordance with the flow of air through the venturi 3, establishing a new valve position.

Line 24 connects chamber 5 and the air inlet tube 1 on the downstream side of the throttle 2 for motor idling. During the idling operation of the motor the throttle valve is nearly closed, thereby producing small suction in the venturi, which may be insufficient to overcome the action of the loading spring and give accurate metering at low speeds. Low pressure existent on the downstream side of the throttle valve when the valve is nearly closed is utilized to supplement venturi action and provide adequate metering during idling. Adjustment of suction through tube 24 is obtained by regulation of valve 25.

To make the carburetor responsive to the throttle and to the suction through tube 24 for idling the volume of chamber 5 and the cross sectional area of opening 4 should be as small as possible and yet allow free working of the dia-

phragm 7 and passage of air through the opening 4.

Opening 13 through the Venturi wall and tube 12 attached thereto are of relatively small cross section so that the liquid fuel will be converted to vapor mainly in the mixing portion 19 of the air intake tube 1.

The valve head 14 is equipped on its underside or face with a material such as synthetic rubber, in order to make an effective closure when the motor is not in operation. This material need not necessarily be synthetic rubber, and I do not wish to limit myself in this respect, since various metals and other materials which are not soluble in hydrocarbons or do not exhibit the property of imbibition or smelling in the presence of such liquids, and yet will make an effective shut-off or seal, may be used.

Valve 16 should be made as small as possible in order that the relatively small pressure differential acting on diaphragm 7 will be of sufficient magnitude to open said metering valve against the liquid fuel pressure in fuel feed chamber 18. The amount of liquid fuel required to flow per second even under full load is only a fraction of a cubic inch per second for many engines and under pressure, hence the metering valve may be quite small.

While the one embodiment of my invention as represented by the drawing and fully described in the foregoing specification, is a satisfactory and useful design, I do not wish to be limited to this one design. Many of the component parts may be altered as to size and shape and yet remain within the intended scope of my invention.

I do not wish to be limited in any manner by the selection of materials, since that point is merely a matter of experience and choice. Many

materials, as long as they are not acted upon by liquid or fuel vapors or air mixtures, may be satisfactory.

I claim:

- 5 A liquid feed carburetor comprising an air inlet tube, a main throttle valve in the air inlet tube, a venturi in the air inlet tube upstream of the main throttle valve, a fuel passage extending through the wall of the air inlet tube at the 10 throat portion of the venturi communicating with a source of fuel supply under pressure, an air passage extending through the air inlet tube at the throat portion of the venturi in alignment with said fuel passage communicating with an air pressure chamber, a variable opening fuel valve for controlling flow of fuel through said fuel passage, force transmitting means connected to the fuel valve and extending through said fuel and air passages, pressure responsive means in said air pressure chamber operably connected with the force transmitting means and tending to increase the opening of the fuel valve on increase of air flow through said venturi, a restriction in said fuel passage, pressure responsive means operably connected with the force transmitting means responsive to pressure differential induced by fuel flow past said restriction and tending to decrease the opening of the fuel valve on increase of fuel flow past said restriction, spring means connected with said force transmitting means tending to close said fuel valve, a conduit connecting said air pressure chamber with the air inlet tube downstream of the main throttle valve to reduce the pressure in said chamber for idling and adjustable valve means for controlling air flow through said conduit.
